UNITED STATES PATENT OFFICE.

NATHAN BILLSTEIN AND JAMES F. SNEDIKER, OF PHILADELPHIA, PENNSYLVANIA; SAID SNEDIKER ASSIGNOR TO SAID BILLSTEIN.

PRINTING-PRESS.

SPECIFICATION forming part of Letters Patent No. 414,791, dated November 12, 1889.

Application filed December 14, 1888. Serial No. 293,556. (No model.)

To all whom it may concern:

Be it known that we, NATHAN BILLSTEIN and JAMES F. SNEDIKER, of the city and county of Philadelphia, and State of Pennsylvania, have invented an Improvement in 5 Printing-Presses, of which the following is a specification.

Our invention relates to printing-presses; and it consists of certain improvements, 10 which are fully set forth in the following specification, and shown in the accompanying drawings, which form a part thereof.

Our invention is more particularly adapted to rotary presses for printing cards, envelopes, 15 or similar small articles where great rapidity is desired; and the object of our invention is to enhance the efficiency of such a press by increasing the rapidity with which it may perform its work. Heretofore a large amount, 20 relatively, of time was consumed in the act of feeding the articles to be printed to the press, and our invention is intended to greatly reduce the amount of labor required for this purpose by means of feeding mechanism and 25 certain improvements in the impression and type cylinders, whereby the articles may be fed to the machine, printed, and delivered with great rapidity and precision.

In our machine the articles to be printed 30 are carried by certain feeding mechanism provided with suitable guides to the impression and type cylinders. The type-cylinder is provided with a type-form loosely secured to it and capable of falling slightly outward beyond the surface of the cylinder for the purpose of receiving ink from the inking-cylinder without any portion of the surface of the type-cylinder coming in contact with the inking-cylinder, and thereby soiling the article 35 to be printed. The impression-cylinder we prefer to form cut away to facilitate the feeding, as hereinafter more fully set forth, so that only a small portion of its surface comes in contact with the type-cylinder, and only at 40 the moment the article to be printed passes between the cylinders and receives an impression from the type.

In the drawings, Figure 1 is a side elevation of a rotary printing-press embodying the 45 principles of our invention. Fig. 2 is a sec-

tional plan view of the same through the line *x x* of Fig. 1. Fig. 3 is an end elevation of the same. Fig. 4 is a longitudinal sectional view of the type-cylinder. Fig. 5 is a sectional view through the line *y y* of Fig. 2. 55

A is the type-cylinder, and B the impression-cylinder, carried, respectively, upon shafts *a* and *b*. The shafts of these cylinders are journaled, preferably, in uprights C by means of the boxes *c*, having the springs D 60 between them, and by means of adjusting-screws E, working against the upper boxes *c*, the cylinders may be adjusted to or from each other. The impression-cylinder B is cut away to form a cylinder-sector, so that only a portion of its surface during rotation will come in contact with the article passing between the cylinders A and B, and only during the period of making an impression. This cutting away of the impression-cylinder is to allow the cards or envelopes to be fed to the impression-surfaces, and although we prefer to cut away the impression-cylinder to form a cylinder-sector it may not be necessary to cut away so large a portion for this purpose. 65 70 75

F is a feeding and guide table resting on the main frame of the machine G, and having an opening at about its center.

H is a shaft journaled in bearings *h* on the main frame of the machine over the portion 80 of the table F that is cut away. This shaft is provided with a series of radial arms I, preferably extending from disks I', carried by the shaft H. These arms I are preferably provided with fingers or forked ends *i* to receive the card or envelope, as hereinafter more fully described. The table F may be provided with slots to allow these radial arms I to pass through it; or its central opening may be made sufficiently large for this purpose, as shown in dotted lines in Fig. 2. We find it expedient also to use three sets of these radial arms I, and preferably four in each set, though this is not essential to our invention. 85 90 95

J is a guide upon the table F to guide the cards or envelopes, and is adjustable horizontally thereon. When desirable, a second side guide J, as shown in dotted lines in Fig. 2, upon the opposite side, may be employed. These 100

guides may be made adjustable to or from each other to suit the exact size of the cards or envelopes to be printed, which are fed between them.

5 K is the inking-roller carried upon a shaft *k*, journaled in the upright C.

L is a distributing-roller running in contact with the inking-roller, and having a reciprocating motion (for the purpose of evenly distributing the ink) imparted to it by the cam L' and projection L², working therein.

In practice we prefer to use an intermediate roller K' between the ink-distributing roller L and the inking-roller K, as shown in 15 Fig. 2, to prevent the wearing out of the soft surface of the inking-roller by the reciprocating movement of the distributing-roller; but this is not an essential feature of our invention.

20 M is a gear-wheel upon the end of the shaft *b* of the impression-cylinder gearing with a gear-wheel N on the shaft *a* of the type-cylinder.

The inking-roller K and the ink-distributing roller L are provided, respectively, with 25 wheels O and P, gearing together, and the wheel O gears with the wheel N, whereby motion is imparted to the cylinders and rollers. When the intermediate roller K' is employed, as above described, an additional gear-wheel O² is used to impart motion to the roller K', but to allow it to be journaled loosely.

Q is a crank pivoted to a disk or fixed arm 30 Q' on the end of the shaft *a*.

R is a link pivoted to the end of the crank Q and to the shaft H, carrying a pawl S.

T is a disk or wheel upon the end of the shaft H, provided with indentations or slots *t* 40 upon its periphery corresponding in number to the radial arms I. In these slots or indentations *t* the pawl S is adapted to engage, and a spring *s* may be employed to assist that object. As the shaft *a* rotates in the direction shown by the arrow, (see Fig. 5,) carrying 45 with it the disk or arm Q', it will impart to the crank Q a backward-and-forward reciprocation, and thereby swing the link R backward and forward a quarter of a revolution.

50 The pawl S, engaging in one of the slots or indentations *t*, will impart to the shaft H and radial arms I a quarter of a revolution upon the forward stroke of the crank Q, while on the backward stroke the pawl will be freed 55 from the slot or indentation and engage with the next, thereby imparting an interrupted rotation to the shaft H and its radial arms I.

U is a friction-clutch upon the end of the shaft H to prevent backward rotation.

60 A portion of the type-cylinder A is cut out to receive the type-form or stereotype-plate W, which is curved upon its face. This type-plate is loosely held in the cylinder by a projecting edge *a'* and screws X, which are 65 adapted to retain the cut-away edges *w* of the plate, allowing slight freedom of movement up and down, so that when the plate is in its

lowest position the type will project beyond the surface of the cylinder, and coming in contact with the inking-roller K will take ink 70 therefrom without any portion of the surface of the type-cylinder touching the inking-roller, whereby the envelope or card would be soiled.

It is found in practice that the weight of 75 the stereotype-plate W affords sufficient pressure against the inking-roller to thoroughly ink it. The sides of the plate W and of the portion of the type-cylinder cut out to receive this plate are preferably formed straight, so 80 that the edges of the plate W are guided upon the edges of the portion cut away, and while the plate W is free to move vertically it is fixed laterally.

Motion is imparted to the machine through 85 a band and band-wheel connected with the shaft *a*, or otherwise, as desired.

From the foregoing description of the mechanism the operation of the machine will be 90 readily understood.

The cards, envelopes, or other articles to be printed are fed by the operator to the radial arms I, which, as heretofore described, are intermittently rotating. The side guide J permits this to be done with great rapidity 95 and precision, and when two of these guides are used they are adjusted toward each other to suit the size of the cards or envelopes, which are guided between them to the radial arms I. The card or envelope is held in the fingers or 100 forked ends *i* and carried over by the rotation of the shaft H and fed between the impression and type cylinders, the former of which is cut away, as heretofore described, to offer no obstruction in the way of the card or 105 envelope as it is carried around by the radial arms I. It is then seized between the surfaces of the type and impression cylinders and carried between them, receiving the impression, and the shaft H remains motionless 110 during the backward stroke of the crank Q until the card or envelope is carried from under the radial arms I, when upon the forward stroke of the arm Q it is again rotated a quarter of a revolution to bring the next 115 card or envelope to the cylinders. With each rotation of the cylinder A the stereotype-plate or type-form W comes in contact with the inking-roller K.

While we prefer to use three of the radial arms I in each set upon the shaft H, the central arm acts as a guide for the operator in placing the envelopes or cards upon the radial arms, and may therefore be made heavier than the arms upon the ends, or may be entirely dispensed with.

We do not limit ourselves to the mere details of construction which are here shown, as it is apparent that they may be varied in many ways without departing from the principles of our invention.

What we claim as new, and wish to secure by Letters Patent, is—

1. In a rotary printing-press, an impression-

cylinder in combination with a type-cylinder, and a rotatable carrier having supports for the articles to be printed, said supports moving in a curve while feeding the articles to the cylinders.

5. 2. In a rotary printing-press, an impression-cylinder in combination with a type-cylinder, and a rotating carrier, substantially as described, to feed the articles to be printed between the cylinder with an intermittent motion.

10. 3. In a rotary printing-press, an impression-cylinder in combination with a type-cylinder, a rotating carrier, substantially as described, to feed the articles to be printed between the cylinders, and a connection between said type-cylinder and feeding mechanism to impart an intermittent rotation thereto.

15. 4. In a rotary printing-press, an impression-cylinder having a portion of its surface cut away, in combination with a type-cylinder, and a rotating carrier, substantially as described, to feed the articles to be printed between the cylinders, provided with radial 25 arms adapted to receive and carry the articles to be printed to the cylinder.

20. 5. In a printing-press, the combination, with a type-form and an impression-surface, of a rotatable carrier having supports for the articles to be printed, said supports moving in a curve while carrying the articles to the type-form and impression-surface.

25. 6. In a rotating press, the combination of an impression-cylinder with a type-cylinder having a portion of its surface recessed, and a vertically-movable gravity-actuated type-form fitting in said recessed portion and free to move vertically therein as the type-cylinder rotates, substantially as and for the purpose specified.

30. 7. In a printing-press, a rotating type-cylinder provided with a type-plate loosely secured thereto, having the faces of its type substantially even with the surface of the cylinder

35. 45. at the moment of making an impression, but adapted to fall slightly as the cylinder rotates to bring the faces of the type beyond the surface of the cylinder for the purpose of receiving ink from an inking-roller.

40. 50. 8. In a printing-press, a rotating type-cylinder provided with a type-plate loosely secured thereto, having the faces of its type substantially even with the surface of the cylinder at the moment of making an impression,

45. 55. but adapted to fall slightly as the cylinder rotates to bring the faces of the type beyond the surface of the cylinder for the purpose of receiving ink from an inking-roller, in combination with an impression-cylinder, a portion of which is cut away, so

60. 65. that the surface thereof comes in contact with the type-cylinder only at the period of printing.

9. In a printing-press, a rotating type-cylinder provided with a type-plate loosely secured thereto, having the faces of its type substantially even with the surface of the cylinder at

the moment of making an impression, but adapted to fall slightly as the cylinder rotates to bring the faces of the type beyond 70 the surface of the cylinder for the purpose of receiving ink from an inking-roller, in combination with an impression-cylinder, a portion of which is cut away, so that the surface thereof comes in contact with type-cylinder 75 only at the period of printing, and means, substantially as described, to feed the articles to be printed to the cylinders intermittently.

10. 10. In a printing-press, a rotating type-cylinder provided with a type-plate loosely secured thereto, having the faces of its type substantially even with the surface of the cylinder at the moment of making an impression, but adapted to fall slightly as the cylinder rotates to bring the faces of the type 85 beyond the surface of the cylinder for the purpose of receiving ink from an inking-roller, in combination with an impression-cylinder, a portion of which is cut away, so that the surface thereof comes in contact with type-cylinder 90 only at the period of printing, and means, substantially as described, to feed the articles to be printed to the cylinders intermittently, consisting of the rotating shaft H, provided with the radial arms I. 95

11. The combination of a type-cylinder and an impression-cylinder with the shaft H, having the radial arms I, and connections between said type-cylinder and shaft H, whereby the latter is intermittently rotated by the rotation of the former. 100

12. The combination of a type-cylinder and an impression-cylinder having a portion of its surface cut away, with the shaft H, having the radial arms I, and connections between 105 said type-cylinder and shaft H, consisting of the crank Q, link R, carrying the pawls S, and disk T, fixed to the shaft H, provided with indentations or slots t, in which the pawl S is adapted to engage to intermittently rotate the 110 shaft H.

13. The combination of a type-cylinder and an impression-cylinder having a portion of its surface cut away, with the shaft H, having the radial arms I, connections between said 115 type-cylinder and shaft H, whereby the latter is intermittently rotated by the rotation of the former, and an anti-friction device U to prevent backward rotation of the shaft H.

14. In a rotary printing-press, the combination, with the impression-cylinder having a portion of its surface cut away, of the type-cylinder, the horizontal guide-table F, provided with an opening, and rotating arms moving through said opening in the guide-table and adapted to carry the articles to be printed to the cylinders. 120 125

15. In a rotary printing-press, the combination, with the impression-cylinder having a portion of its surface cut away, of the type-cylinder, the horizontal guide-table F, provided with an opening, rotating arms moving through said opening in the guide-table and adapted to carry the articles to be printed to 130

the cylinders, and a vertical side guide upon said table to assist the feeding of the articles to be printed to said rotating arms.

16. In a rotary printing-press, the combination, with the impression-cylinder having a portion of its surface cut away, of the type-cylinder, the horizontal guide-table F, provided with an opening, rotating arms moving through said opening in the guide-table and adapted to carry the articles to be printed to the cylinders, and mechanism, substantially as described, operated by one of said cylinders to intermittently rotate said radial arms.

17. In a rotary printing-press, the combination, with the impression-cylinder having a portion of its surface cut away, of the type-

cylinder, the horizontal guide-table F, provided with an opening, rotating arms through said opening in the guide-table and adapted to carry the articles to be printed to the cylinders, and vertical side guides arranged upon said table and adjustable to or from each other to assist the feeding of the articles to be printed to said rotating arms.

In testimony of which invention we here-
unto set our hands.

NATHAN BILLSTEIN.
